YARN CONTROLLER FOR CREELS AND
LIKE APPARATUSErnest R. Swanson, Cranston, R. I., assignor to
Universal Winding Company, Boston, Mass.,
a corporation of Massachusetts

Application April 28, 1933, Serial No. 668,425

11 Claims. (Cl. 242—1)

This invention relates to an improved yarn- or thread-controller for use on creels and like apparatus wherein a plurality of cones, spools or other forms of packages are arranged to deliver their ends to a warper or other winding or reeling machine.

In the following specification the term "yarn" is employed in its generic sense to indicate all kinds of strand material; and the term "package" is intended to indicate any form of yarn-mass.

One object of the invention is to provide a device for controlling the individual yarns delivering from the supply-packages to prevent them from kinking or becoming entangled when the ends become slack due to the stopping of the warper or other rewinding machine.

Another object of the invention is to provide a yarn-controller of the type indicated which is operated automatically upon cessation of the draft on the yarn to positively grip or seize the latter to prevent it from sagging to entangle with other yarns or to loop and kink when the end becomes slack.

Another object of the invention is to provide a device of the type indicated which is controlled automatically by the draft on the yarn without applying undue or excessive tension thereto.

Another object of the invention is to provide a device of the type indicated which is simple in construction, economical to manufacture and proof against derangement or getting out of order.

Further objects of the improvement are set forth in the following specification which describes a preferred embodiment of the invention, by way of example, as illustrated by the accompanying drawings. In the drawings:

Fig. 1 is a view in elevation of a section of a creel showing a plurality of the improved yarn-controllers applied to use thereon for controlling the multiple ends delivering from the supply-packages mounted on the creel frame;

Fig. 2 is a perspective view of the yarn-controller and its mounting;

Fig. 3 is a side elevation of the controller showing it as operative to grip the length of yarn passing therethrough;

Fig. 4 is a front view of the same;

Fig. 5 is a plan view of the controller and its mounting;

Fig. 6 is a view similar to Fig. 3 showing a different setting of the controller elements;

Fig. 7 is an enlarged sectional view taken on line 7—7 of Fig. 3 and illustrating the manner in which the controller elements seize or bind the yarn; and

Fig. 8 is a similar sectional view showing the controller elements open under normal conditions during the draft on the yarn.

The present improved yarn-controller comprises a movable element around or across which the strand of yarn draws in feeding from the creel to the warper or other winding machine and a fixed element toward which the movable element is moved automatically upon cessation of the draft on the yarn to seize or bind the strand between said elements to prevent its free length from sagging in a loop to entangle with other yarns delivering from the creel or from snarling or kinking.

Fig. 1 of the drawings illustrates a conventional type of creel frame whereon a plurality of supply-packages or yarn-cones C are supported to deliver their ends to a warper or other winding machine in which the yarns are wound into a ball or onto a spool or beam. As herein shown the creel is of the magazine type wherein the cones C are arranged in pairs with the last end of yarn from one cone spliced to the leading end of a companion cone to provide for continuous delivery of the yarn therefrom. The creel frame 25 comprises two series of rods or uprights 2 and 3 mounted in feet 4 and 5 which rest on the floor. The rods or uprights 3 of one set are arranged alternately of the rods 2 of the other set and spaced at a distance forwardly therefrom to adapt them to mount the yarn-controllers, indicated generally by the reference character 6. The uprights 2 and 3 are connected at the top by horizontal rods 7 and 8, respectively, and a strut or brace 9 extends downwardly therefrom with its foot 10 fastened to the floor.

The creel frame usually comprises two opposite wings arranged at an angle to each other with the apex end facing the warper or other winding machine to provide for delivering a large number 40 of ends from both sides of the creel; only one wing being herein shown. The cones or supply-packages C are mounted on holders carried by arms or brackets 11 which are swiveled to turn about the rearward uprights 2 of the frame. 45 When the yarn on the delivering cone is exhausted its holder may be swung back to provide for doffing the empty tube or yarn-carrier and recreeling a fresh supply which is magazineed to the companion cone then delivering its yarn. 50 Normally, the holders for the two cones C of each pair are turned to a position with their axes converging at a point in line with a single yarn-controller 6 which serves this respective pair of cones. The brackets or arms 11 which 55

carry the cone-holders are held in operative position by means of detent-projections 12 engaging in notches 13 formed in collars 14 which are secured to the uprights 2 to locate the brackets in position thereon.

5 The thread or yarn-controllers are mounted on supports or brackets 15 constructed in the form of clamps for attachment to the forward vertical rods or uprights 3. As shown most clearly in Figs. 2, 3 and 5, each bracket 15 is provided with a forked or yoke-like portion 16 adapted to straddle the sides of the rod 3 and preferably having an arcuate portion 17 which extends partly around the rod. A set-screw 18 is threaded through the side of the yoke 16 with its end adapted to engage against the side of the rod 3 to secure the bracket fixedly in place thereon.

10 The mounting proper for the controller is in the form of a shelf or base-plate 20 provided with a stud 21 on its side inserted through a bore in the main portion of the bracket 15. A nut 22 on the end of the stud 21 serves to clamp the shelf 20 fixedly to the bracket 15 while adapting it to be turned about the axis of the stud to adjust it to different positions for a purpose as later explained.

15 The fixed element 25 of the controller 6 may be constructed of wire bent into a narrow hairpin-shaped loop 26 at the top with the lower sides 20 of the loop diverging outwardly and rearwardly at 27 and continued downwardly in the parallel legs 28. The inner sides of the bight of the loop 26 are cut away at the top to form an enlarged opening 29 which is somewhat wider than the space between the vertical sides of the loop.

20 The movable element 30 of the controller 6 may also be constructed from a length of wire formed into a helical coil 31 substantially midway of its ends with two angularly disposed arms 35 and 36 extending therefrom. The coil 31 provides a journal or bearing for pivotally mounting the element 30 on the support or shelf 20. For this purpose the support or shelf 20 is formed at one side with a yoke 32 through the sides of which is driven a pin 33. Rotatably mounted on the pin 40 33 is a sleeve or bushing 34 to which the helical coil or bearing 31 of the element 30 is secured. The two arms 35 and 36 of the element 30 are disposed at substantially right-angles to each 45 other, the arm 35 being adapted to assume a substantially vertical position in parallel relation to the sides of the loop 26 of the fixed element 25, while the arm 36 extends horizontally. At the upper end of the arm 35 the wire is bent at right-angles in an elbow-like extension 37 adapted to slide freely through the enlarged opening 29 in the bight of the loop 26. The elbow 37 terminates in an upwardly bent portion 39 adapted to make engagement with the top of the loop 26 to limit the tilting or rocking movement of the element 30 on its pivot. The opposite horizontal arm 36 of the element 30 extends outwardly from the pivot bearing to provide a counterbalance, the weight of which tends to hold the arm 35 in vertical position bearing against the sides of the loop 26 as shown in Fig. 3 and also indicated in Fig. 7 of the drawings. In some cases weights may be added to the arm 36 to further counterbalance the upright arm 35 of the movable element 30.

70 The yarn-controllers 6 are mounted on the vertical rods 3 of the creel frame with their upper portions substantially in alignment with the points of convergence of the axes of the cones 75 C, it being noted that the axes of the cones tilt

downwardly slightly from the horizontal. The set-screws 18 on the clamping brackets 15 provide for adjusting the controllers 6 at the proper height on the creel frame, a single controller being provided for each pair of magazine yarn-cones C. The supports or shelves 20 for the controllers project from the side of the rod 3 to locate the upright arms 35 of the movable elements 30 on the side nearest the cones with the opposite arms 36 extending forwardly from the front of 10 the creel frame.

5 The construction and arrangement of the yarn-controllers having now been described in detail their method of operation will next be explained. After the cones C have been placed on 15 their holders with the ends of their yarns magazine or tied together as indicated at e in Fig. 1, the yarn y leading from the first cone to be unwound is inserted between the arm 35 of the movable controller element 30 and the loop-portion 20 26 of the fixed element 25. The ends from all of the initially delivering cones are threaded through the controllers 6 in this manner and the yarns then drawn forwardly across the front of the creel. Usually, the several ends are threaded 25 through eyes in a series of separator-arms 40 attached to a vertical rod 41 forming a part of the creel frame. From the guides or separators 40 the yarns lead directly to the warper or other rewinding machine, being sometimes passed 30 through a comb or lease-reed extending across the back of the machine. The multiple ends of the yarn are attached to the beam, spool or like support on which they are to be wound by the warper or other machine and as the winding proceeds the strands draw off over the ends of the first series of cones C. After the material has been exhausted from the first cones, delivery is continued from the associated cones in the pairs while the operator recreels fresh supplies on the 40 first set of holders and splices their ends to the last ends of the delivering cones.

45 In operation, as the yarn is taken up by the warper or other rewinding machine, each strand y delivering from its respective cone draws around the vertical arm 35 of the movable controller element 30 which is thereby rocked back to a position away from said loop 26 of the fixed element 25 as indicated in Fig. 2 of the drawings. That is to say, as the yarn is drawn taut it will swing 50 the arm 35 away from the loop 26 of the fixed element 25 whereby to provide for a free passage of the yarn through the controller without the application of any appreciable tension thereto; the only resistance which the yarn encounters 55 being the slight friction of the strand on the arm 35. As the strand y feeds through the controller it is permitted to slide up and down along the arm 35 in shifting from the upper to the lower side of the cone as it unwinds therefrom. 60 The play of the yarn in this manner is restricted at the top by the elbow portion 37 of the arm 35 and at the bottom by the horizontal portion 27 of the fixed member 25; whereby to prevent the strand from whipping out of or otherwise es- 65 caping from the controller.

If it is desired to apply a slight amount of tension to the yarn the whole controller may be tilted at an angle to the vertical, as shown in Fig. 6, by rotating the shelf or support 20 on 70 the axis of its stud 21; the nut 22 being loosened to provide for this adjustment and then tightened after the proper setting has been secured. If a still greater degree of tension is desired for relatively coarse yarns, one or more weights may 75

be applied to the horizontal arm 36 of the controller element 30 to resist its rocking movement away from the loop 26 of the fixed member 25. In most cases, however, especially with fine yarns, it is desirable that the tension on the delivering yarn be reduced to an absolute minimum, only sufficient to prevent the strand from unwinding too freely from the cone.

When the warping or other rewinding operation is arrested, for example, upon breakage of an end, the yarn-controller operates automatically in the manner as next explained to positively seize the strand to prevent it from sagging and looping to cause kinking or snarling. In drawing off over the end of the cone or other yarn package the yarn delivers very freely so that when the warper or other rewinding machine is stopped there is a tendency for the ends to sag where they extend in long lengths across the front of the creel and between the creel and the warper. The present improved yarn-controller prevents such sagging of the yarn by seizing it at a joint adjacent the package to hold it taut in the length extending beyond this point.

Immediately the warper or other rewinding machine stops and the draft on the yarn is arrested, the counterbalanced controller element 30 will be caused to rock to the right, as viewed in Fig. 3, or toward the loop of the fixed element 25 to seize the yarn by pinching it between the wires. As the arm 35 of the element 30 rocks into the position illustrated in Fig. 3 of the drawings the bight of yarn looped around the arm 35 of the element 30 is pinched against the two sides of the loop 26 of the fixed element 25 as indicated in Fig. 5 of the drawings and also illustrated in the enlarged view, Fig. 7.

Normally, when under the draft of the rewinding process the yarn *y* passes freely through the controller without contact with the sides of the loop 26 of the fixed element 25, as indicated in Fig. 8 of the drawings; but immediately upon cessation of the draft on the yarn the element 30 is moved under the action of gravity on its arm 36 to rock its upright arm 35 toward the loop 26 to bind the yarn thereagainst as shown in Fig. 7. It will be understood, of course, that the action of the wire arm 35 of the element 30 in pressing the strand against the sides of the loop 26 of the element 25 is relatively light so that the yarn is not mashed or jammed. However, the pressure of the arm 35 is sufficient to cause the strand to take a tortuous course across the sides of the members 25 and 30 whereby to resist any tendency of the strand to draw through the controller to allow it to sag in the length extending therebeyond. In this manner the controllers act to maintain all of the yarns in taut condition, it being understood that a multitude of ends are usually delivered from a single creel and due to the compact grouping of the supplies the ends are liable to interfere one with another if allowed to sag or droop downward.

Heretofore in creels and similar apparatus of the present type it has been considered necessary to employ tension-devices acting on the individual yarns to maintain them taut when the rewinding process is arrested. Such tension-devices apply considerable resistance to the yarns during their delivery and the amount of tension is increased or augmented as the lineal rate of draft increases. Difficulty has been experienced in the use of such tension-devices on creels, particularly with fine yarns, as in most cases the applied tension is excessive and tends to

cause breakage of the strands, besides limiting the speed at which the yarn can be wound in the warper. Moreover, with a large number of ends it is difficult to regulate the applied tension uniformly and constantly, since resistance to delivery of the yarn varies with the size of the package from which it is unwinding and an increase in resistance at the supply causes the applied tension to be augmented.

With the present improved yarn-controller 10 practically no tension is applied to the yarns during their delivery from the supplies to the warper or other winding machine; but immediately upon cessation of the draft on the yarns the controller acts to seize and hold the strands 15 so that there is no possibility of the ends sagging. Immediately the warping or other rewinding process is started the first pull on the yarns causes the movable elements 30 to be swung away from the fixed elements 25 so that the strands 20 are released to feed freely again without danger of stretching or breaking the yarn.

It will be observed from the foregoing that the present improved device operates automatically without the use of connected elements such as 25 rods, slides, springs or the like to provide the motive force. The movable controller element functions promptly and efficiently to seize the yarn upon cessation of the draft thereon; and likewise it is sensitive and rapid in action to release the yarn in response to the draft, whereby to prevent stretching, straining or breaking the material. The device is extremely simple in construction, proof against derangement or getting out of order and its parts are not subject to any 35 considerable wear or deterioration over long periods of use.

While the device is herein shown and described as embodied in a preferred form of construction, it is to be understood that modifications 40 may be made in the structure and arrangement of its parts without departing from the spirit or scope of the invention. Therefore, without limiting myself in this respect, I claim:

1. A yarn-controller for creels and like apparatus comprising a fixed element, a movable element mounted opposite the fixed element and adapted to engage and contact the latter to positively grip a yarn therebetween, guiding means for controlling the direction of feed of a strand 50 of yarn drawing through the device to cause it to make an angular bend around the movable element to normally hold the latter away from the fixed element, and means automatically operative when the draft on the yarn ceases to cause 55 the movable element to move toward the fixed element to positively grip the yarn thereagainst.

2. A yarn-controller for creels and like apparatus comprising a fixed element, a second element mounted to adapt it to move into contacting engagement with the fixed element, means for guiding a strand as it is fed through the controller, said guiding means being laterally positioned on opposite sides of the movable element and spaced apart to cause the strand to 65 be bent from a straight course as it draws across the movable element to hold the latter away from the fixed element and out of contact therewith, and means operative when the feed of the strand is arrested to move the movable element toward 70 the fixed element to positively grip the yarn thereagainst.

3. In a device of the type indicated, the combination of a fixed element having spaced portions, an arm mounted for movement in a plane 75

extending between the spaced portions of the fixed element and so constructed and arranged as to engage the spaced portions of the fixed element throughout a considerable portion of their length, said arm adapted to be moved away from the fixed element by a yarn drawing thereacross to prevent the yarn from contacting the fixed element whereby to reduce the tension on the yarn to a minimum, and means operative when the draft on the yarn ceases to carry the movable element toward the spaced portions of the fixed element to positively grip the yarn between said arm and fixed element.

4. In a device of the type indicated, the combination of a fixed element having opposite parallel portions, a movable element having an arm adapted to move into contact with the parallel portions of the fixed element throughout a substantial portion of their length, means for guiding a strand to adapt it to draw across the movable element, said guiding means being so positioned as to direct the strand toward and away from the movable element in an angular course to hold said movable element away from the fixed element, and means operative upon cessation of tension on the strand to cause the movable element to move toward the fixed element and positively grip the strand thereagainst whereby to prevent it from sagging and kinking.

5. In a device of the type indicated, the combination of an element having opposite parallel legs disposed with a relatively narrow space therebetween, a single arm extending substantially parallel with the legs of the fixed element and mounted to move toward and away therefrom in a plane extending between said parallel legs, said movable arm being of greater width than the space between the legs of the fixed element to contact therewith throughout a considerable portion of their length but normally held away from the fixed element by the passage of the yarn thereacross, and means operative when the draft on the yarn ceases to move the movable arm toward the opposite parallel legs of the fixed element to positively grip the yarn thereagainst.

6. In a device of the type indicated, the combination of a fixed element formed with parallel sided portions, an element movable with respect to the fixed element and having one arm extending in parallel relation to the sides thereof and a second arm extending at right-angles thereto, said movable element being counterbalanced to swing towards the fixed element, and means for limiting the swinging movement of the arm away from said fixed element.

7. In a device of the type indicated, the combination of an element having a close-sided loop extending in opposite parallel legs, a pivoted element having an arm extending between the legs of the fixed element and adapted to assume a

position in contact with the sides of its loop, means to limit the pivotal movement of said arm away from said loop under the action of a yarn drawing thereacross, and gravity-operated means for swinging said arm toward the loop to bind the yarn thereagainst upon cessation of the draft on the yarn.

8. In a device of the type indicated, the combination of a support, an element mounted on said support and formed with an upstanding loop portion, an arm pivoted to said support and extending in opposite parallel relation to the sides of the loop of said element, means on said arm for engaging the loop to limit its swinging movement with respect thereto, and a counterweight on said arm for normally maintaining it in position bearing against the sides of the loop.

9. In a device of the type indicated, the combination of an element having a hairpin-shaped loop, and an arm pivoted with respect to said element to adapt it to swing into position to contact with the sides of the loop of the first element, said arm having a portion extending through the loop in the first element and provided with means at its end for engaging the loop to limit the swinging movement of the arm.

10. In a device of the type indicated, the combination of a mounting adapted for adjustment about a horizontal axis, a fixed element supported by said mounting and formed with spaced legs, a second element pivoted to the mounting and provided with an arm extending in substantially parallel relation to the legs of the fixed element and movable in a plane extending between the legs, said arm being so constructed and arranged as to engage the legs throughout a considerable portion of their length but normally held out of engagement with the legs by a moving strand drawing across the arm, and means for counterbalancing said arm to cause it to swing toward the spaced legs of the fixed element when the draft on the yarn ceases.

11. In a device of the type indicated, the combination of a bracket, a mounting supported from said bracket to adapt it to be adjusted angularly about a horizontal axis, a fixed member projecting upwardly from said mounting and provided with opposite parallel leg portions, an arm pivoted to said mounting to adapt it to extend in parallel contiguous relation to the leg portions of the fixed member, means for guiding a strand of yarn comprising a support for a yarn supply and a yarn-guide so positioned as to cause the yarn to be angularly bent across the arm to hold the latter away from the fixed member, and a second arm extending at an angle to the first arm to adapt it to counterbalance the latter and to swing it toward the opposite parallel fixed portions of the fixed member when the draft on the yarn is relieved.

ERNEST R. SWANSON.
